(57) **CLAIM**

The ornamental design for a folding wagon, as shown and described.

DESCRIPTION

FIG. 1 is a perspective view showing the front, left side and top of a folding wagon which forms my new design; FIG. 2 is a perspective view showing the rear, right side and top thereof;

FIG. 3 is a top plan view thereof;

FIG. 4 is a left side elevational view thereof;

FIG. 5 is a right side elevational view thereof;

FIG. 6 is a bottom plan view thereof;

FIG. 7 is a front elevational view thereof; and,

FIG. 8 is a rear elevational view thereof.

The short broken lines shown in FIGS. 1, 2, 4, 5, 7 and 8 are understood to represent stitching.

The long broken lines shown in FIGS. 1, 2 and 4-6 represent portions of the article that form no part of the claims.
